UNITED STATES PATENT OFFICE.

JAMES C. WALLACE, OF COLORADO CITY, COLORADO.

FILTER-BED.

SPECIFICATION forming part of Letters Patent No. 664,196, dated December 18, 1900.

Application filed September 1, 1900. Serial No. 28,761. (No model.)

To all whom it may concern:

Be it known that I, JAMES C. WALLACE, a citizen of Great Britain, (but having declared my intention of becoming a citizen of the United States,) residing at Colorado City, in the county of El Paso and State of Colorado, have invented a new and useful Improvement in Filter-Beds, of which the following is a specification.

10 My invention relates to filter-barrels such as are used in the chlorination process of extracting precious metals from pulverized ores, and has special reference to a filtering-bed within said barrel. I have described elsewhere (in Patent No. 653,631, dated July 10, 1900, filed February 14, 1900, Serial No. 5,231) the general process of extracting the precious metal by a similar method, so that it need not be repeated here. All such filtering-
15 barrels require within them a filtering surface or medium, practically separating the barrel into two generally unequal compartments, the larger one holding the ore, which is supported upon the upper surface of a filtering-bed, and the lower or smaller compartment holding the liquid solution which has drained through the filtering medium. It is the particular form, construction, and material of this filtering-bed which constitutes the
20 25 30 35 subject-matter of my present invention and which I will now proceed to describe, reference being had to the accompanying drawings, in which—

Figure 1 represents a vertical longitudinal center section through one end (lower arc) of a horizontal filter-barrel. Fig. 2 represents a cross-section through this lower arc on line $x x$ of Fig. 1.

The letter a in each case represents the circumferential wall of the barrel. A series of metal plates b extend practically the whole length of the barrel, their adjoining edges abutting each its neighbor and secured by bolts or rivets c at their opposite ends to the inside of wall of the barrel a . These plates in Fig. 2 are shown as curved, which is the form I prefer using, although they may be flat, a consideration being, however, that a space e be left between their under surface
45 50 and the barrel-wall. This plate is seen in en-

larged sectional view in Fig. 3 and in plan view in Fig. 4, with a cross-section through line $y y$ in Fig. 5. The plate is perforated by longitudinal slots $d d$, through which the liquid finally drains to the space e . The longer parallel edges of each plate are turned up at right angles or finished with a small angle-iron edge, as at f . Upon this plate and confined between the edges $f f$ I place a series of small tiles, which may be made of glazed pottery-ware or of a lead composition, the consideration being that they be made of a material not affected (or very slightly) by the chemical solution within the barrel. These tiles are represented in position in Figs. 65 2, 3, 4, and 5 by $g g g$ and in larger detail by Fig. 6, which shows a plan view of a portion of two abutting tiles, a longitudinal vertical view, (beneath the plan,) and an end view of one of them. These tiles are perforated along 70 their abutting surfaces by semicylindrical or conical holes $h h h$, very small in area and preferably tapering, as shown, the lower area of the holes connecting with or opening into a slotted area i in the lower surface of each 75 tile. These tiles form the filtering-bed, the liquid draining through the small holes h into the under slotted area i , thence through the slots $d d$ of the plates b , whence it drops and is collected in the lower compartment e of the 80 barrel a . The tiles $g g g$ are held down in position by the imposed metal binders $k k$, which are fastened by the keys m in the head n , this head n being riveted by its neck o to the plate b , as shown. A short angle-iron p 85 is fastened to the plate b at either end by means of the neck o or by separate rivets, the purpose of this angle-iron being to confine the end tiles g . It must be understood that all these metal parts are coated with lead to 90 prevent chemical action thereon by the liquid.
Having described my invention, what I claim as new and original, and desire to secure by Letters Patent, is—
1. In a filter barrel or tank, a tile having 95 two rows of vertical semicircular holes along its two opposite vertical surfaces and connecting with a drain area, channel, or cavity recessed in the lower surface of said tile; substantially as shown.

2. In a filter-barrel, a filter-bed consisting of a series of metal plates having drain slots or perforations therethrough, a series of perforated tiles arranged as a filtering medium upon and supported by said metal plates, a series of metal binding-strips imposed upon or against said tiles; together with suitable

means for fastening or confining the same together and to the inner wall of a filter barrel or tank; substantially as described and shown. ¹⁰
